UNITED STATES PATENT OFFICE.

HARRY MACKENZIE RIDGE, OF LONDON, ENGLAND.

MUFFLED ROASTING-FURNACE.

1,070,534.

Specification of Letters Patent.

Patented Aug. 19, 1913.

Application filed March 9, 1911. Serial No. 613,225.

To all whom it may concern:

Be it known that I, HARRY MACKENZIE RIDGE, a subject of the King of Great Britain, residing at 62 London Wall, in the city 5 of London, England, mining engineer, have invented certain new and useful Improvements in Muffled Roasting-Furnaces, of which the following is a specification.

This invention is a roasting furnace having mechanically operated stirrers mounted upon two or more vertical shafts in which the flues for the roasting gases are constructed so that there is no communication between them and the roasting hearth or 15 hearths. Since the mechanical stirring or rabbling of the ore is regular and does not involve opening the working doors of the furnace, the disadvantages attendant upon stirring the ore by hand in known muffled 20 roasting furnaces are entirely obviated.

In the accompanying drawings Figure 1 is an elevation of one arrangement of roasting furnace constructed in accordance with my invention; Fig. 2 is a longitudinal section on line A—B of Fig. 3, which is a horizontal section on line C—D of Fig. 2; Fig. 4 is a transverse section of the furnace in the plane of one of the rabble shafts; Figs. 5, 6 and 7 are longitudinal sections 30 showing modified arrangements of flues.

The furnace therein shown has three superimposed muffles *a*, *b*, *c* which are heated by the heating flue *d*, which first passes beneath the hearth of the bottom muffle *c*, 35 thence upward and along in the reverse direction between the muffles *b* and *c*. On the longitudinal center line of the muffles is a series of vertical shafts *e* each of which, except the one at the right hand end, passes 40 through all three muffles and is supported beneath the furnace in a footstep bearing. The shafts are revolved in the usual manner by means of worm gearing *f* running in oil and inclosed in dust-proof covers, and gas-tight joints are made at the top of the 45 furnace by means of water seals *g* at the points where the vertical shafts pass through the arch or crown of the furnace. Where these shafts pass through the heating flue they 50 are insulated by means of firebrick or other refractory non-conducting material which serves the double purpose of preventing transference of heat to the shafts and leakage of the furnace gases into the muffles. 55 The shafts are fitted with rabble arms *i* and are arranged at varying distances apart so

that the path of the stirrers or rabbles in some cases cuts into the zone of the adjacent rabble only very slightly, while in other cases the two zones overlap to a very considerable extent, so as to insure a thorough mixing of the ore. Where the rabble path only cuts but slightly into the adjoining zone, the rabbles are so designed that the passage of the ore from the one zone to the other can take place only in one direction. By this means the material while being roasted, passes gradually along the furnace until it reaches the last rabbling zone of a given hearth, in the case of furnaces with 60 multiple superimposed hearths, where it is stirred in gradually decreasing circles until it reaches an opening near the shaft, in that zone, through which opening the material drops to the inclosed muffle below it. The 65 openings may be in any convenient position. Two of such openings are indicated in Fig. 2, one being shown in full lines at *l* and the other in broken lines at *m*.

The raw material is introduced into the 70 top muffle through a suitable opening such as *k* and passes successively through the various rabbling zones in the top muffle or hearth *a* until it reaches the last zone from which it passes through the drop hole *l* on 75 to the hearth of the next muffle *b* which it traverses in the opposite direction until it reaches the drop hole *m* through which it passes to the lowest muffle *c*, traversing it and eventually passing out of the furnace 80 through the discharge opening *n*. The 85 roasting gases travel in the opposite direction to the ore from the furnace *h* under the bottom muffle *c*, thence by the vertical passages *j* to the gas flue *d* between the top of 90 the muffle *c* and the hearth of the muffle *b* and along this flue in the direction opposite to the travel of the ore in the muffle *b*, thence 95 either to the atmosphere as shown in Fig. 2 at *d'* or alternatively as in Fig. 5 by vertical 100 flues *j'* to a gas flue *d''* between the top of the muffle *b* and the hearth of the muffle *a* and along this flue to a gas outlet *d'''*. Alternatively, the gas flue instead of passing between the top of the second muffle and the 105 hearth of the uppermost muffle, as in Fig. 5, may be taken as in Fig. 6 by vertical passages *j''* to a flue *d''* above the top of the top muffle *a* to an outlet *d''*. Again the gas flue in addition to passing between the middle 110 and uppermost muffles may be taken, as in Fig. 7, above the latter muffle by means of

vertical passages j^3 and flue d^6 to an outlet d^7 .

As that part of the hearth of the lowest muffle which is near to or extends over the 5 furnace grate is subject to very rapid wear owing to high and unequal temperatures, it is preferred that this end of the lowest muffle together with the furnace should extend beyond the end wall of the upper muffle so 10 as to enable this part to be cut off from the remainder by blocking the flue d near the furnace end and to be renewed or repaired without serious interruption to the operation of the furnace.

15 The number of superimposed muffles may vary according to circumstances and the nature of the material to be roasted and similarly the number of vertical shafts and the arrangement of the rabbling zones may likewise be varied to suit particular requirements.

Having thus described the nature of this invention and the best means I know of carrying the same into practical effect, I 25 claim:—

1. A muffled roasting furnace, comprising in combination a furnace, a muffle having a material feed inlet and discharge outlet, a plurality of mechanically rotated vertical 30 shafts passing through the muffle, a radial rabble arm fitted to each shaft, the said shafts being arranged at varying distances apart so that the paths of the ends of adjacent rabble arms in some cases overlap 35 slightly and in other cases overlap to a considerable extent, means for gradually passing the material fed into the muffle toward the discharge outlet, and a flue communicating with the furnace and passing below 40 the hearth of the muffle whereby the latter may be heated without admixture of the heating gases from the furnace with the gases from the gases from the material being treated.

2. A muffled roasting apparatus, comprising in combination, a furnace, a series of superimposed and intercommunicating muffles, an inlet in the uppermost muffle for the introduction of materials to be treated, a discharge outlet in the lowermost hearth, a

plurality of mechanically rotated vertical 50 shafts passing through the muffles, radial rabble arms carried by the shafts, the said shafts being arranged at varying distances apart so that the paths of the ends of adjacent rabble arms in each muffle in some 55 cases overlap slightly and in other cases overlap considerably, means for passing the material fed into the apparatus successively along the muffles toward the said discharge outlet, and flues communicating with the furnace and passing in proximity of the muffles whereby the latter may be heated without admixture of the heating gases from the furnace with the gases from the material under treatment.

3. A muffled roasting apparatus, comprising in combination, a furnace, an upper muffle, a lower muffle having an end superimposed above the furnace and extending beyond the end of the upper muffle, the upper muffle having an inlet for the introduction of material to be treated and an outlet communicating with the lower muffle, a discharge outlet in the lower muffle, a rotatable vertical shaft passing through the projecting end of the lower muffle, a plurality of similar shafts passing through the muffles, radial rabble arms carried by the shafts, the said shafts being arranged at varying distances apart so that the paths of the ends of adjacent rabble arms in each muffle in some cases overlap slightly and in other cases overlap considerably, means for passing the material fed into the apparatus successively along the muffles toward the said discharge 75 outlet, and flues communicating with the furnace and passing in proximity of the muffles whereby the latter may be heated without admixture of the heating gases from the furnace with the gases from the material under treatment.

In testimony whereof I have signed my name to this specification in the presence of two subscribing witnesses.

HARRY MACKENZIE RIDGE.
